ATTORNEY.

UNITED STATES PATENT OFFICE.

HERBERT RÜHLEMANN, OF SOMMERDA, GERMANY, ASSIGNOR TO RHEINISCHE METALLWAAREN- UND MASCHINENFABRIK, OF DUSSELDORF-DERENDORF, GERMANY.

ELECTRIC PERCUSSION FUSE.

Application filed April 16, 1928, Serial No. 270,464, and in Germany April 27, 1927.

The invention relates to electric percussion fuses of the type in which the flow of the current from the source of current through the igniting means, viz an incandescent bridge piece, is made adjustable to variable strength by means of a regulating resistance inserted in the circuit of the percussion fuse, whereby an impact ignition with or without delay is obtained according to a greater or smaller 10 resistance amount being switched-in.

According to the invention the fuse comprises two igniting means adapted to be selectively switched into the circuit of its source of current or other accumulator of 15 electric power, one of these igniting means operating with delay and the other without delay. In comparison with the above-mentioned known arrangement, in which only a bridge piece consisting of an incandescent 20 wire can be employed as igniting means, the new arrangement affords the advantage, that now also a spark igniter may be used as igniting means, which is of particular advantage in the impact ignition without delay, to increase the quick action of the fuse, that means to reduce the lag of ignition after the impact contact has been closed.

In order to allow of my invention to be more easily understood, a wiring diagram 30 of my improved fuse is illustrated by way of example in the drawing which accompanies and forms part of this specification.

The source of electric power of the fuse is constituted e. g. by an electric condenser a , which is loaded through its poles a_1 and a_2 , reaching up to the surface of the projectile shell, by a source of current (not shown) arranged separately from the projectile, before or the instant the projectile is fired.

40 A normally open impact contact b and a throw-over switch c is arranged in the discharge circuit, by which switch either the igniting means d_1 or d_2 may be switched-in selectively.

45 Both these igniting means d_1 and d_2 may be designed as incandescent bridge igniters or as spark igniters. The igniter d_1 operates with delay, whilst d_2 operates without delay. To this end the igniter d_1 is formed

50 e. g. by an incandescent bridge igniter, before which a high ohmic resistance is arranged. When the igniter d_1 has been thrown into the discharge circuit of condenser a by means of switch c , then, when

the impact contact b is closed by the projectile hitting an aim and the current then flows through the igniter d_1 , the heating wire of the latter is heated up only after a certain lapse of time to the temperature required for the ignition, so that the latter 60 does not take place immediately on impact, but only with a certain delay.

The delay igniter d_1 may further be fitted with a heating wire that ignites immediately when the current flows therethrough or 65 with a spark gap that firstly influences a delay composition of known type.

The igniting means d_2 intended to operate without delay, suitably consists of a spark igniter that works more quickly than a 70 bridge igniter and instantaneously ignites upon the impact contact b being closed, whereby the impact ignition takes place particularly quickly.

75 The switch c may be designed in such a manner, that in its position "no delay", that is when the non-delay igniter d_2 has been switched in, for the sake of reliable action at the same time also the delay igniter d_1 is thrown-in, so that, upon the instantaneous 80 percussion ignition failing to act, a delay ignition still takes place as with the known mechanical percussion fuses with adjustable delay. In a third (illustrated) position of the switch c both igniters d_1 and d_2 are disconnected from the condenser a . The handle serving to manipulate switch c may be made independent of the latter as to its switch motion, so that even after setting the handle to "no delay" or "delay" the switch c 85 firstly perseveres in disconnecting position and automatically arrives in the set position by inertia only when the projectile is fired.

90 What I claim, is:—

1. In an electric projectile percussion fuse of the class described a source of current, a circuit connected thereto, an impact contact in said circuit, two electric igniters and means for connecting them selectively to 100 said circuit, one of said igniters being adapted to operate with and the other to operate without delay.

2. In an electric projectile percussion fuse of the class described a source of current, a circuit connected thereto, an impact contact in said circuit, two electric igniters connected in parallel to said circuit, a switch arranged in 105

said circuit and adapted to selectively switch-in one of said igniters, one of them being adapted to operate with and the other to operate without delay.

- 5 3. In an electric projectile percussion fuse of the class described a source of current, a circuit connected thereto, an impact contact in said circuit, two electric igniters connected in parallel to said circuit, a switch 10 arranged in said circuit and adapted to selectively switch-in one of said igniters, one of them being adapted to operate with and the other to operate without delay, said first-

named igniter comprising a heating wire, and the last-named igniter a spark gap. 15

- 4. In an electric projectile percussion fuse of the class described a source of current, a circuit connected thereto, an impact contact in said circuit, two electric igniters and means for connecting them both selectively and commonly to said circuit, one of said igniters being adapted to operate with and the other to operate without delay. 20

In testimony whereof I have affixed my signature.

HERBERT RÜHLEMANN.
